UNITED STATES PATENT OFFICE.

LEWIS MILLER, OF AKRON, OHIO.

PAWL-AND-RATCHET MECHANISM FOR HARVESTERS.

SPECIFICATION forming part of Letters Patent No. 293,767, dated February 19, 1884.

Application filed April 11, 1883. (No model.)

To all whom it may concern:

Be it known that I, LEWIS MILLER, of Akron, in the county of Summit and State of Ohio, have invented certain new and useful Improvements in Pawl-and-Ratchet Mechanism for Harvesters; and I do hereby declare the following to be a full, clear, and exact description of the same, reference being had to the accompanying drawings, forming part of this specification, in which—

Figure 1 represents a vertical sectional view of a driving-wheel and axle with my improvements applied thereto, the pawls being shown disengaged from the hub. Fig. 2 is a sectional view taken on the line $x x$, Fig. 1. Fig. 3 is an edge view of part W' and attachments, and Fig. 4 a detailed view, showing one of the pawls engaged with the hub.

This invention relates to improvements in harvesters; and it consists in certain novel improvements in the backing-ratchets applied to the driving-wheels, whereby said ratchets can be thrown into or out of gear at will, and will be automatically retained in the position in which they are so adjusted, all as herein-after described and claimed.

Referring to the drawings, W represents the hollow or concave inner end of the hub of the traction or driving wheel, having ribs or teeth w , and cast on the periphery of the concave; and W' represents a circular plate which fits into said concave, it being fixed on the axle and provided with a hub to hold it steady. Its face adjacent to the hub W may be concave, if preferred. The edges of the plates W' are slotted, as shown at w' , obliquely to its radius and in a direction inclining forward or with the direction of the rotary movement of the parts on the axle. With each slot (two, more or less) there is combined a pawl, w^2 , pivoted to the inner face of the plate, and having a spur or arm, w^3 , adapted to project through the slot, the form of the slot being such as to allow the spur or arm to move freely therein as the pawl swings on its pivot. The inner side (toward the center of the shaft) of each pawl is provided with an elongated central hub, w^4 , terminating in a notch or recess, w^5 . In connection with each pawl there is employed a flat spring, v , secured to the same plate, W' . The free end of the spring is provided with an angle or projection, v' , which

bears against the elongated hub w^4 , to hold the pawl in engagement with the series of teeth or ribs w . The parts are so proportioned and adjusted that when the pins or spurs w^3 are near the outer end of the slots w' the springs v bear against the enlarged part w^4 of the pawl and press the latter outward against the ratchet-teeth w ; but by moving the arms or spurs w^3 downward or inward to the bottom of the slots w' the bearings or projections v' of the springs pass off of the enlarged part w^4 and enter the recess at its end, where they no longer press the pawl outward, but, on the contrary, bear in a direction toward the pivots of the pawls, or even in lines which, extended, would pass between said pivots and the main axle, and thereby serve to hold the pawls by frictional contact out of engagement with the ratchet-teeth. Thus it will be seen that the springs perform the double function of holding the pawls to the ratchets when their engagement is desired and of holding them away from the ratchets when their engagement is not desired. The arms w^3 , projecting through the plates W' , enable the attendant at any time to put the pawls into or out of engagement without removing the wheels or disturbing any other parts. In going to or from the field he can readily ungear the entire mechanism by means of these arms w^3 , leaving the traction-wheels to run loosely on their axle, and on arriving at the field a moment's time serves to put the parts all in gear by the simple operation of moving the arms w^3 outward in their slots.

To prevent the springs from getting out of adjustment with relation to the pawls, the latter are provided with a thin lug or blade, v^2 , which fits against the face of the disk W' between the spring and the disk, and which, moving with the pawl, keeps the spring in the proper relation thereto.

I am not aware that this contrivance or its functional equivalent has ever before my invention thereof been known or used in machines, and I therefore do not limit it to harvesters only, but desire to protect it for use in all kinds of machinery to which it may be applicable. An inferior equivalent of the construction of the spring-pawls above described may be obtained by omitting the arms w^3 and moving the pawls by inserting a fork

to embrace them or a pointed instrument to enter a hole or cavity in their side. In such case any suitable guide or stop may be provided to guide and limit the movement of the 5 pawls from one adjustment to the other. Nor do I limit this part of my invention to the locking of the pawls out of gear by means of the springs, inasmuch as an independent lock may be applied to hold the pawls out of gear, 10 although for simplicity and convenience I prefer to lock the pawls out of gear by the springs as well as to hold them in gear by the same means.

15 The particular machine to which my herein-described improvements are especially applied is the one for which application for Letters Patent was filed by me on the 31st day of December, 1879, and of which this present case is a division.

20 Having thus described my invention, I claim as new—

1. The combination of the pawl provided with the elongated hub or lug, the plate to which it is pivoted, and the spring provided

with the angle or shoulder and acting on the 25 pawl-lug to hold the pawl in either of two positions according to adjustment, substantially as hereinbefore set forth.

2. The combination of the rotated ratchet, the shaft upon which it is loosely mounted, the 30 pawl-carrier fastened to said shaft, the adjustable pawl, and the spring by which the pawl is held in or out of action, substantially as hereinbefore set forth.

3. The combination of the slotted pawl-carrier, the shaft to which it is keyed, the rotating hub having the internally-toothed peripheral flange and loosely mounted on said shaft, the pawl, the pin or arm secured thereto and projecting through the slot of the pawl-carrier, the pawl-lug, and the spring provided with the angle or shoulder and acting on the pawl-lug, substantially as described, for the purpose hereinbefore set forth.

LEWIS MILLER.
